US0D1090863S

(12) **United States Design Patent** (10) **Patent No.:** **US D1,090,863 S**
(45) **Date of Patent:** **** Aug. 26, 2025**

(54) **HEEL PATCH**

(71) Applicant: **Nanjing Anziwu E-commerce Co., Ltd.**, Jiangsu (CN)

(72) Inventor: **JiaHao Liu**, Jiangsu (CN)

(73) Assignee: **Nanjing Anziwu E-commerce Co., Ltd.**, Nanjing (CN)

(**) Term: **15 Years**

(21) Appl. No.: **29/989,809**

(22) Filed: **Feb. 15, 2025**

(51) LOC (15) Cl. **24-02**

(52) U.S. Cl.

USPC **D24/189**

(58) **Field of Classification Search**
